UNITED STATES PATENT OFFICE.

ROBERT E. DRAGO, OF MEADVILLE, PENNSYLVANIA, ASSIGNOR TO EDWARD H. FALLOWS, OF NEW YORK, N. Y.

TIE-PLATE.

1,059,446.

Specification of Letters Patent. Patented Apr. 22, 1913.

Application filed January 25, 1912. Serial No. 673,465.

To all whom it may concern:

Be it known that I, ROBERT E. DRAGO, a citizen of the United States, and a resident of Meadville, in the county of Crawford and 5 State of Pennsylvania, have made and invented certain new and useful Improvements in Tie-Plates, of which the following is a specification.

My invention relates to an improvement 10 in tie plates, designed to be placed beneath the rails, and to rest upon the ties of a railway track, one object thereof being to provide a plate of this character in which provision is made for preventing the same from 15 creeping or moving sidewise upon the tie, such movement to be prevented by means of spurs so located and arranged upon the under side of the plate as to offer a maximum resistance to the movement thereof.

20 A further object of my invention is to provide spurs so formed and arranged that they will readily and easily enter the tie, and with but little or no injury thereto.

With the above and other ends in view, 25 the invention consists in certain novel features of construction as will be hereinafter fully described and pointed out in the claim.

In the accompanying drawings, Figure 1 is a plan view of my improved tie plate; 30 Fig. 2 is a view showing the under side thereof; Fig. 3 is a view showing an end elevation thereof with a portion of a rail and securing spikes; and Fig. 4 is a view in side elevation of my improved tie plate 35 as seen from a position to the left of Figs. 1 and 2.

Referring to the drawing, the reference 40 numeral 4 designates my improved tie plate as a whole, the upper surface thereof being provided with side ridges 5, against which the outer edge of the base of the rail abuts when the plate is in place, as will be understood from Fig. 3. The tie plate is provided with holes 6, through which fastening spikes 7 pass into the tie beneath the plate, lugs 8 being provided at the outer sides of the holes to afford support for the spikes as illustrated in Fig. 3. The under side of the plate is provided with downwardly projecting 45 side spurs 8, these spurs being located beneath that portion of the plate engaged by the side edges of the rail when the latter is in place, to thereby strengthen the plate at the place where it is somewhat weakened by

5 prevent it from being broken along a line corresponding approximately with the side edge of the base of the rail, it being understood that a sidewise thrust upon the head of the rail tends to tip the same about its 60 side edge. The spurs therefore strengthen the plate at the points where it is subjected to the greatest strain, and also at the points where it is weakened by the holes through which the securing spikes pass. 65

The number of side spurs 8 employed is immaterial, and depends largely upon the service to which the plate is to be subjected. In the drawings, I have illustrated three such spurs upon the outer side of the 70 rail, and two upon the inner side, although it will be understood that the number thereof may be increased or decreased, as desired. These spurs extend transversely to the rail as shown, the outer ends 9 thereof being 75 made square, or at right angles to the face of the plate, in order to thereby increase the resistance to outward movement of the plate when the same is in service.

In order to still further resist sidewise 80 movement of the plate, I provide a downwardly projecting spur 10 upon the under side of the tie plate and designed to enter the tie. This spur is located between the side spurs 8, and preferably beneath the 85 central web of the rail as shown in Fig. 3, so that the weight imposed thereon acts directly over said central spur to force it into the tie. The spur 10 is preferably of considerable length, and so arranged as to extend longitudinally of the rail. 90

The side spurs 8 will be seen to extend in the same direction as the grain of the wood of the tie, so that they will enter the latter with a minimum of injury thereto. The central spur 10, however, preferably extends transversely to the grain of the tie, but being located beneath the central portion of the plate, it follows that if any injury be done by it to the tie, it is localized, and at a considerable distance from the side spurs. 95

Having thus described my invention, I claim and desire to secure by Letters Patent:—

A tie plate having downwardly projecting 105 side spurs upon its under side located beneath that portion of the plate engaged by the side edges of the base of the rail and extending transverse to the rail and part

tral portion of the plate is unobstructed by
said spurs; a centrally arranged downwardly projecting spur extending longitudinally of the rail and located beneath the
5 web thereof; and a side ridge located upon the upper side of and adjacent one side of the plate and against which the edge of the base of the rail abuts.

Signed at Meadville in the county of Crawford and State of Pennsylvania this 10
19th day of January A. D. 1912.

ROBERT E. DRAGOON.
